UNITED STATES PATENT OFFICE.

GEORGE H. HOLDEN, OF BURLINGTON, VERMONT.

DESIGN FOR AN OVEN.

SPECIFICATION forming part of Design No. 32,751, dated May 29, 1900.

Application filed May 2, 1900. Serial No. 15,274. Term of patent 14 years.

To all whom it may concern:

Be it known that I, GEORGE H. HOLDEN, a citizen of the United States, residing at Burlington, in the county of Chittenden and 5 State of Vermont, have invented and produced a new and original Design for Ovens, of which the following is a specification, reference being had to the accompanying drawing, in which the figure is a perspective view 10 of an oven, showing my new design.

The leading feature of the design consists in the design forming the subject-matter of the accompanying illustration.

The general form of the oven is rectangular 15 and slightly elongated vertically with the flat sides A and front B, the whole being mounted on the corner-legs C. The front B for about two-thirds its length from its top is formed with the transversely-elongated panels D, 20 having the central handholds D', while forwardly-projecting plates D² at the ends of said panels and close to the edges of the oven present a serrated appearance when viewed

from the sides of the oven, as shown in the figure of the drawing.

The lower third of the front of the oven is 25 ornamented centrally by the rectangular plate or panel E, having the forwardly-projecting base-plate E' and the upper and lower forwardly-projecting and inclined portions 30 E² and E³, while the front is further ornamented on opposite sides of the panel E by the circles E⁴.

Having thus described my invention, what I claim as new, and desire to secure by Letters 35 Patent, is—

The design for an oven as herein shown and described.

In testimony whereof I have signed my name to this specification in the presence of 40 two subscribing witnesses.

GEORGE H. HOLDEN.
